UNITED STATES PATENT OFFICE

2,256,041

LUBRICATING SYSTEM

Frank S. Bell, Baltimore, Md., assignor to Crown Cork & Seal Company, Inc., Baltimore, Md., a corporation of New York

Application July 20, 1939, Serial No. 285,607

17 Claims. (Cl. 184—10)

The present invention relates to means for supplying lubricant to a plurality of relatively movable instrumentalities mounted for movement along an orbital path. More particularly, the invention relates to means for supplying lubricant to various elements requiring lubrication, which are mounted on a rotatable table, in a machine such as a bottle filling or closing machine. It must be understood, however, that the invention is not limited to filling or closing machines, but will be found useful wherever it is desired to supply lubricant to machine elements travelling along a predetermined definite path.

It is a primary object of the invention to supply lubricant to such instrumentalities, without using flexible conduits, stuffing boxes, packing glands, or other relatively movable, liquid-tight connections between oil conduits mounted, respectively, on a rotary table or the like, and on a stationary base or the like.

It is a further object of the invention to provide a continuous supply of oil for instrumentalities carried by a rotatable table, in accurately controlled amounts, and to prevent leakage, splashing or other waste of oil.

In the specific embodiment of the invention illustrated in the accompanying drawings and described below, the lubricating system is shown in connection with a bottle filling machine, of the type wherein a plurality of vertically movable bottle supporting platforms carried by elongated cylindrical sleeves are mounted in vertical bearings in a rotatable table. The reciprocating movements of the supporting sleeves and platforms are controlled, at least in one direction, by cam following rollers carried by the sleeves. The sleeves also carry guide rollers cooperating with vertical guide tracks to maintain the sleeves upright.

The invention provides means for supplying oil to the bearings in which the sleeves are slidably mounted and for the journals for the cam following and guide rollers. In accordance with the prior art, these parts have been lubricated either by hand from time to time, or by lubricant conduits associated with the table and the base, respectively, and connected through relatively movable packing glands or the like. The present invention entirely eliminates such connections and provides an automatic constant supply of oil.

It is an object of the invention to provide, in a machine of this class, a novel oil transfer element supported upon the base, adapted to receive a continuous, thin, thread-like stream of oil

from a source of supply, and to provide novel oil collecting devices supported for movement with the table and adapted to take oil from the transfer device in definite, controlled, predetermined amounts during the rotation of the table, to supply the moving parts on the table with lubricant.

Other and further objects and advantages of the invention will be apparent to one skilled in the art from a consideration of the following description of the illustrative embodiment shown in the accompanying drawings, in which:

Figure 1 is a fragmentary vertical radial section through a portion of a filling machine, with certain parts broken away.

Figure 2 is a view taken on line 2—2 of Figure 1, in part a section and in part a plan.

Figure 3 is a view taken on line 3—3 of Figure 2.

Figure 4 is a view taken on line 4—4 of Figure 2.

Figure 5 is a bottom plan view on line 5—5 of Figure 4.

Figure 6 is an enlarged, fragmentary, vertical section on line 6—6 of Figure 4.

Figure 7 is a similar view on line 7—7 of Figure 3.

Figure 8 is a transverse section on line 8—8 of Figure 7.

Figure 9 is a vertical section on line 9—9 of Figure 6.

Figure 10 is a section on line 10—10 of Figure 6.

Figure 11 is an enlarged vertical section of a detail.

Figure 12 is an end view of the part shown in Figure 11, and

Figure 13 is a perspective view of the lubricant transfer arm shown in Figures 1 and 3, and

Figure 14 is a fragmentary sectional view through the bearing sleeve shown in Figure 1, but taken on a vertical plane at right angles to the plane of Figure 1.

The invention of the present application is shown in association with a bottle filling machine, generally similar to that described and illustrated in detail in the patent to Huntley and Stewart 2,145,765, patented January 31, 1939. Of course, the invention can be used with other machines, and the reference to the foregoing patent is simply for purposes of illustration. Such a machine comprises a stationary base 15 upon which a rotatable filling table 16 is journaled. A raised portion 17 of the base supports a bracket 18 carrying a cam track 19, adapted to be engaged by a roller 20 mounted on a collar 21, secured to a sleeve 22 carrying, at its upper end, a bottle supporting platform 23. An an-

nular platform 24 is suspended below the table 16 by depending guide brackets, not shown, and a sheet metal casing 25 encloses the bottle supporting sleeves 22 and the like. A coil spring 26, interposed between the platform 23 and the upper end of a fixed, lower, hollow, cylindrical bearing 27, surrounds a rod 28 and urges the rod, the sleeve 22 and the bottle supporting platform 23 upwardly. A vertically disposed bearing 29 surrounds the sleeve 22, and it is the purpose of the present invention to supply lubricant thereto. Since the bottle supporting sleeves 22 and their associated parts are not a part of the present invention, they will not be described further, reference being had to the aforementioned patent for a more complete description.

The cam track supporting bracket 18 is provided with a substantially horizontal platform 30, upon which a pair of upwardly projecting brackets 31, 32 are bolted (Figs. 1 and 3). The bracket 31, at its upper end, is provided with upwardly projecting apertured ears 33, 34 and with laterally projecting flanges 35, 36, one having a seat 37 for a spring 38, and the other having a bore in which a stop bolt 39 is threaded. Upon a transverse pin 40, disposed in the apertures in the ears 33, 34, there is fulcrumed a lubricant transfer device 41, comprising a rearwardly extending, short arm 42, having a seat 43 for the spring 38, and a forwardly projecting arm 44. This arm is bent upwardly and laterally at 45, and then forwardly at 46. The undersurface 47 of the elongated portion 46 of the arm is straight transversely, but is convex longitudinally, as shown in Figures 3 and 13. Also, the elongated arm is preferably curved longitudinally in plan, to correspond with the curvature of the path of movement of the instrumentalities on the table, as indicated in Figure 2. As indicated in Figure 7, the cross-sectional shape of the arm 46 is such that the side faces taper upwardly and merge in a blunt point at 48, for purposes hereinafter described.

The other bracket 32, mounted on the platform 30, has a lateral projection 50 at its upper end, carrying, in a bore 51, an oil pipe 52, having at its lower end, a threaded socket 53 adapted to receive a conduit leading from a source of oil under accurately controlled, predetermined pressure. At its upper end, the pipe section 52 has a laterally facing, threaded socket 54, carrying a nipple 55, which has a downwardly opening socket 56 in its outer end, in which is disposed a ball 57 pressed downwardly by a spring 58, against a ring seat 59 provided with a plurality of slots or kerfs 60 (Fig. 12), and held in position by the flanged-over rib 61, integral with the end of the nipple 55. The ball 57 assumes the lowermost position, as shown in Figure 11 and oil is supplied thereto through the passages in the fittings 52, 55, and through the slots 60, with the result that a film of oil flows downwardly over the surface of the ball to the lowermost point on the surface thereof, where the oil preferably forms into a thin, thread-like stream, as at 62 (Fig. 11). The oil is received by the upper pointed end 48 of the arm 46, where it spreads out and flows downwardly over the side faces thereof, and over the highly polished bottom face of the arm in the form of a thin film.

As stated above, the oil flows continuously to the ball 57 from an accurately controlled source of oil under relatively low pressure, such as a pump and pressure relief valve, the details of construction of which are not a part of the inven-

tion of the present application. Since the pressure of the oil is preferably maintained constant, the flow will be continuous and of constant volume, except when changes in viscosity of the oil, due to temperature changes, result in variations in the volume of flow and in slight pressure variation, due to slight changes in back pressure. If desired, means may be provided for changing the method of supplying oil, at the source, and also means for changing the pressure, at the source of oil, to compensate for changes in viscosity, thereby maintaining the volume of flow substantially constant. In some cases, when the supply of oil is associated with the complete lubrication system for the other parts of the machine, such as a high pressure intermittent lubrication system, the intermittent high pressure intervals of that system are reflected in the present continually flowing low pressure part of the system, causing a momentary high pressure therein. Thus, minor variations in the pressure, viscosity and volume of flow are permitted, within the scope of the present invention. The thread of oil between the ball 57 and the upper end 48 of the arm 47 is preferably maintained unbroken during the operation of the machine, but if the parts are improperly adjusted or if other changes occur, the oil may be delivered from the ball 57 to the arm 47 in the form of drops. The oil is removed from the transfer device by means associated with the bearings to be lubricated.

An oil receiving cup 65 is disposed in a bore 66 in the socket 67 carrying the bearing 29 for the bottle supporting sleeve 22. The cup 65 may be held in place by a set screw 67' with the horizontal bore 68 of the cup aligned with an inclined groove 69 formed in the inner face of the bearing 29. At its outer end, the cup member is recessed as at 70 to provide an upwardly opening receptacle, in which there is disposed an upstanding, hardened wiper pin 71, having an upper end face 72 positioned to engage the lower face 47 of the lubricant transfer arm 46.

Each bottle supporting assembly carries one of these oil wiping and collecting assemblies. As a result, during each rotation of the table, each pin 71 wipes an appropriate amount of oil from the oil transfer device, the oil being collected in the receptacle 70 and delivered to the groove 69, to lubricate the sleeve.

The cam following rollers 20 are supplied with oil by similar means. Each roller has a bearing sleeve 75 secured in its central bore and mounted for rotation on the periphery of a trunnion 76 projecting laterally from the sleeve 21. An axial bore at 77 in each trunnion 76 receives a plug 78 having a central bore 79' communicating with an oil collector cup 79 through a horizontal bore 80. The cup, secured in the plug 78 by a set screw 81 or the like, has an upwardly facing receptacle 82 and a hardened, wiper pin 83, similar to the corresponding parts 70, 71, described above.

On an enlarged portion 85 of the trunnion 76, a guide roller 86 having a central bearing sleeve 90 is journalled. The roller is disposed between vertical guides, not shown, to maintain the sleeves 22, 27, etc., in vertical alignment. The trunnion 76 and the plug 78 are provided with additional passages 87, 88, 89, so that there is a conduit from the receptacle 82 to the inner face of the bearing sleeves 75, 90, associated with the rollers 20 and 86.

Oil is supplied to the receptacle 82 and thence to the rollers by means similar to that hereto-

fore described. The horizontal platform 30 of the cam track bracket, at a point disposed immediately forwardly of the position of the bracket 32 carries an inwardly projecting bracket 91 (Figs. 2, 4 and 5) having an inwardly projecting, overhanging portion provided with downwardly projecting apertured ears 92, 93 and with forwardly and rearwardly projecting flanges 94, 95, the former having a seat 96 for a spring 97 and the latter having a threaded bore for the reception of a stop bolt 98. A fulcrum pin 99, disposed in the ears 92, 93, carries a lubricant transfer device 100, generally similar, but specifically different from the device 41, heretofore described. The device comprises a rearwardly projecting arm 101 disposed beneath the stop bolt 98 and a forwardly projecting short portion 102 having a socket 103 for the other end of the spring 97. The latter portion, beyond the socket 103, is bent laterally outwardly and downwardly at 104, and then forwardly at 105, where it is elongated so as to overlie the wiper pins 83 associated with the collector cups 79. The end 105 of the lubricant transfer arm is shaped substantially the same as the end 46 of the transfer arm 41. Its lower, lubricant transferring face 105 is substantially flat transversely, but is convex longitudinally. Moreover, as shown in Figures 2 and 5, the arm is curved to lie on an arc concentric with the circumference of the table.

Lubricant is supplied to the transfer arm 100 by a fitting 110, projecting downwardly through the platform 30 and secured in a bracket 111 by a set screw 112 or the like. The lower end of the fitting 110 is substantially the same as the end of the fitting 55 and a ball 57', functioning in the same manner as the ball 57, is secured therein. The upper end of the fitting 110 is provided with a threaded socket 114 to receive an oil conduit leading from the source of oil under predetermined pressure.

As a result of this construction, oil is supplied to the elongated arm 105 of the transfer device 100 by a continuous, thread-like flow from the ball 57'. Each wiper pin 83 picks up a predetermined amount of oil during each rotation of the table and the oil is delivered from the cup 82 through the bores 80, 79', 89, 87, 88 to the rollers 20 and 86, to lubricate the bearings 75, 90 thereof.

In the operation of the machine, at a predetermined point in the rotation of the table, the cam 19 draws the several bottle supporting sleeves 22 and platforms 23 downwardly, successively, against the action of the springs 26. Since the cam profile is not a part of the present invention, it is not shown herein, and, for a more complete disclosure of the operation of the cam, the cam roller, the guide roller 86 and the associated parts, reference may be had to the aforementioned patent. When in the lowermost position, as shown in Figure 1, and during clockwise rotation of the table, the pin 71 associated with each assembly first approaches the undersurface 47 of the elongated arm 46 of the lever 41. The arm 46 is in the lower position as a result of the action of the spring 38. A thin, thread-like stream of oil is maintained by the surface tension of the oil, between the ball 57 and the upper, pointed edge 48 of the lever 46. This continuously flowing stream of oil maintains a film of oil on the undersurface 47 of the arm 46. The pin 71 associated with each bottle supporting assembly contacts the undersurface of

the arm 46, and, during its travel therealong, raises the same slightly, against the action of the spring 38. Preferably, the lifting movement is not sufficient to cause the upper edge of the arm 46 to actually contact the ball 57. The oil collected by the pin 71 flows downwardly therealong into the receptacle 70 where it may be collected, to find its way eventually to the groove 69 in the bearing 29. The upper bearing for the sleeve 22 is supplied with lubricant by oil transferred thereto upon the upward reciprocating movements of the sleeve, since the outer surface of the sleeve is maintained covered with a film of oil, received from the groove 69 in the bearing 29. The lower, internal bearing 27, likewise receives oil from the groove 69 by a flow of oil through appropriate apertures 69' in the sleeve 22, which apertures register with vertical grooves 69'' communicating with the main groove 69. Oil is led to the surface between the rod 28 and the internal bearing 27 by the arcuate slots 27' below the seat for the lower end of the spring 26.

As the machine continues its rotation, the pin 83 associated with the collector 79 for the cam following and guide rollers, approaches the undersurface 106 of the elongated arm 105 of the lubricant transfer device 100. This arm, through the stop bolt 98 and spring 97 is positioned, relative to the pins 83, in substantially the same manner as previously described. The pin 83, during its travel along the undersurface of the arm 105, raises the latter slightly and wipes oil therefrom. The oil is collected in the cup 82, from which it flows to the bearings 75, 90 of the rollers 20 and 86, through bores 80, 79', 89, 87 and 88. Again, in connection with the roller lubricator, the parts are preferably so adjusted that the arm 105 does not actually contact the ball 57', but, on the contrary, is supplied with oil in the form of a thin thread-like stream. If the arm 105 is not properly adjusted, so that there is an excess space between the arm and the ball 57', the oil may be transferred in the form of drops, instead of in the form of a thread-like stream. The oil received in the cup 79 also serves to lubricate the thrust faces of the rollers 20 and 86, as well as the guide rails (not shown) in which the rollers 86 ride.

It must be understood that the invention is not limited to details of construction shown in the accompanying drawings and described above, but covers all mechanisms coming within the scope of the appended claims and their equivalents.

I claim:

1. In a machine of the type wherein a set of relatively movable instrumentalities requiring lubrication are mounted for movement along an orbital path, means for supplying lubricant to said instrumentalities, said means comprising a relatively stationary lubricant delivery means, an elongated, imperforate lubricant transfer arm having a smooth, continuous undersurface substantially fixed with respect to said path and positioned to receive lubricant from said delivery means, lubricant collecting means mounted for movement with said set of instrumentalities, positioned to receive lubricant by wiping contact with said surface during said movement along said path, and means for conducting the lubricant from said collecting means to said instrumentalities.

2. In a machine of the type wherein a set of

relatively movable instrumentalities requiring lubrication are mounted for movement along an orbital path, means for supplying lubricant to said instrumentalities, said means comprising a relatively stationary lubricant delivery means, an elongated lubricant transfer arm having smooth, continuous, imperforate top side and bottom surfaces, said arm being pivoted on a fixed axis for movement with respect to said delivery means and positioned to receive lubricant therefrom and shaped to cause the same to flow over its side surfaces and to film over the bottom surface thereof, lubricant collecting means mounted for movement with said set of instrumentalities having means for wiping lubricant from said bottom surface during a portion of said movement along said path, and means for conducting the lubricant from said collecting means to said instrumentalities.

3. In a machine of the type wherein a set of relatively movable instrumentalities requiring lubrication are mounted for movement along an orbital path, means for supplying lubricant to said instrumentalities, said means comprising a relatively stationary lubricant delivery means, a solid, imperforate, elongated lubricant transfer arm pivoted for movement relative to said means and positioned to receive, on its outside, lubricant from said delivery means and having a lubricant filming surface disposed substantially parallel to a portion of said orbital path, lubricant collecting means mounted for movement with said set of instrumentalities and having an element positioned to wipe said filming surface during a portion of said movement along said path, and means for conducting the lubricant from the collecting means to the instrumentalities.

4. A lubricating system for a machine of the class wherein a plurality of instrumentalities requiring lubrication are mounted upon a rotatable table for revolution about a stationary base, said system comprising an imperforate, solid metal transfer member pivotally mounted on said base adjacent the path of movement of the instrumentalities, means fixedly supported on said base for delivering a constant supply of lubricant to the exterior of said member, and to cause the same to assume a film form on a surface thereof, a plurality of lubricant receptacles, one mounted for movement with each set of instrumentalities, means for wiping lubricant from said member and for delivering the same to said receptacles, and conduit means leading from the receptacles to the instrumentalities requiring lubrication.

5. In a bottle-filling or closing machine of the type wherein a plurality of vertically movable bottle supporting platforms are mounted on a table supported for rotation upon a fixed base, a lubricating system for delivering oil to the supporting means for the platforms, said system comprising means fixed with respect to said base for delivering a constant thread-like stream of oil, a relatively stationary oil transfer member pivoted for limited movement toward and from said oil delivery means and having an imperforate upper surface positioned to receive said stream of oil, said member being shaped to cause the oil to flow over its side surfaces and to film over its undersurface, the latter being continuous, imperforate and non-absorbent, and collector means supported by the table and arranged to wipe oil from said undersurface of said member during

rotation of the table and to deliver the same to said supporting means.

6. In a machine of the class wherein a plurality of bottle supporting sleeves are mounted for vertical movement in a table supported for rotation about a fixed base, means for lubricating the sleeves comprising lubricant delivery means on said base, an imperforate lubricant transfer arm positioned adjacent the path of movement of the sleeves and mounted for pivoting movement relative to the lubricant delivery means to receive lubricant upon its exterior surfaces directly therefrom, a collector carried by the table and positioned to wipe lubricant from said transfer arm, and means for conducting lubricant from said collector to said sleeve.

7. In a machine of the class wherein a plurality of instrumentalities are mounted for relative movement in a table supported for rotation about a fixed base, and wherein movement of the instrumentalities is controlled during rotation of the table by cam following rollers carried by the table, means for lubricating said rollers comprising lubricant delivery means on said base, a lubricant transfer arm positioned adjacent the path of movement of the rollers and having smooth, continuous, imperforate top, side and bottom faces positioned to receive lubricant from said delivery means by a flow over the side faces of the arm to the bottom face thereof, collectors carried by the table and positioned to wipe lubricant from said bottom face, and means for conducting lubricant from said collectors to said rollers.

8. In a machine of the class wherein a plurality of bottle supporting sleeves are mounted for reciprocating movement in vertically disposed bearings in a table supported for rotation in a horizontal plane about a fixed base, means for automatically supplying lubricant to said bearings comprising an elongated lubricant transfer arm having a continuous, imperforate lower face disposed substantially concentric in plan to the path of movement of said bearings and pivoted about a fixed axis disposed substantially radially of the table, means for supplying lubricant to said surface of said arm, a lubricant collector for each bearing mounted for movement therewith and having means adapted to take oil from said surface, and a conduit for conducting oil from each collector to its bearing.

9. In a machine of the class wherein a plurality of bottle supporting sleeves are mounted for movement in a table supported for rotation about a fixed base and wherein the movements of the sleeves are controlled during rotation of the table by cam rollers carried by and rotatable with the table and positioned to engage a cam on the base, means for automatically supplying lubricant to the journals for said rollers comprising a solid, imperforate, horizontally, elongated lubricant transfer arm positioned adjacent the path of movement of the rollers, means for supplying lubricant to the upper surface of said arm, a lubricant collector for the journal of each roller adapted to take oil from the lower surface of said arm, and a conduit for conducting oil from each collector to its associated journal.

10. Means for supplying lubricant to a lubricant receiving device mounted for translational movement along a predetermined path and having a wiper associated therewith, said means comprising a pivotally mounted, solid, imperforate

lubricant transfer arm having a continuous imperforate, non-absorbent, bottom surface elongated in the direction of said path and positioned in the path of movement of said wiper, and means for delivering lubricant to the top surface of said arm, said arm being shaped to cause the lubricant to flow over the side surfaces and to spread in a film on said bottom surface.

11. Means for supplying lubricant to a plurality of wipers supported by a rotatable table and movable along a circular horizontal path during rotation thereof, said means comprising a solid, elongated lubricant transfer arm pivoted adjacent the path of movement of the wipers and having a smooth, continuous, imperforate, non-absorbent convex undersurface disposed in the path of movement of said wipers, and means for delivering oil to an upper surface of said arm, said arm being shaped to cause the oil to flow over the side surfaces thereof and to assume a film form on said convex undersurface.

12. Means for supplying lubricant to a plurality of upwardly projecting wipers supported for rotation with a rotatable table along a horizontal path, said means comprising a lever pivoted about a fixed axis and having a horizontally elongated, solid arm provided with a continuous, imperforate, longitudinally convex undersurface positioned in the path of movement of said wipers, spring means for urging the arm downwardly, and means for supplying lubricant in thin film form to the undersurface of the arm.

13. Means for supplying lubricant to a plurality of wipers supported by a rotatable table and movable along a circular path during rotation thereof, said means comprising a pivoted lubricant transfer arm having an elongated surface lying in the path of movement of said wipers, and means for supplying a continuous stream of oil in thread-like form to said arm, the last-mentioned means comprising an oil conduit terminating in spaced relation to the arm, a ball in the end of the conduit and a passage for delivering a thin stream of oil to the exposed surface of the ball.

14. Means for supplying lubricant to a plurality of wipers supported by a rotatable table and movable along a circular path during rotation thereof, said means comprising a pivoted lubricant transfer arm having an elongated surface lying in the path of movement of said wipers, and means for supplying a continuous stream of oil in thread-like form to said arm, the last-mentioned means comprising an oil conduit having a downwardly facing end socket, a seat in the open end of the socket, a ball therein pressed downwardly against the seat, and a plurality of cuts in the seat constituting oil passages adapted to form a film of oil on the lower face of said ball.

15. In a machine of the class wherein a plurality of bottle supporting sleeves are mounted for reciprocating movement in vertically disposed bearings in a table supported for rotation about a fixed base and wherein the reciprocating movements of the sleeves are controlled during rotation of the table by cam rollers which are actuated by a cam track associated with a bracket having a horizontal platform, means for automatically supplying lubricant to the journals for said rollers, said means comprising a plurality of lubricant collectors for the rollers mounted for rotation with the table at a relatively low level, a bracket mounted on said platform at a relatively low level, an imperforate, elongated transfer arm pivoted on the bracket and having a smooth, continuous, non-absorbent lubricant transfer surface in the path of movement of said collectors, and means for supplying lubricant to an upper surface of the transfer arm to cause the same to form a film of oil on said transfer surface thereof.

16. Means for applying lubricant to a plurality of wipers supported by a rotatable table and movable along a circular path during rotation thereof, said means comprising a solid, pivoted lubricant transfer arm having an elongated portion provided with a smooth, imperforate, bottom surface lying in the path of movement of said wipers, said surface being convexly curved longitudinally of the arm, the side surfaces of the arm being curved upwardly and inwardly toward the top and meeting at the top in a longitudinally extending, imperforate, blunt edge, and means for delivering oil to said top edge of the arm, whereby said oil flows over said side surfaces and films out on said bottom surface, to be picked up by said wipers.

17. In a machine of the class wherein a plurality of bottle supporting sleeves are mounted for reciprocating movement in vertically disposed bearings in a table supported for rotation in a horizontal plane about a fixed base, means for automatically supplying lubricant to said bearings comprising a solid, imperforate, elongated lubricant transfer arm having a smooth, continuous lower face positioned adjacent the path of movement of said bearings and pivoted about an axis fixed relative to said base, means for supplying lubricant to an upper surface of said arm, whereby the lubricant may flow exteriorly of the arm to said lower face, a lubricant collector for each bearing mounted for movement therewith and having means adapted to take oil from the lower face of the arm, and conduit means for conducting oil from each collector to its bearing.

FRANK S. BELL.
